(57) **CLAIM**

The ornamental design for a powered toothbrush handle, as shown and described.

DESCRIPTION

FIG. 1 is a top, front perspective view of a powered toothbrush handle in accordance with the present invention; FIG. 2 is a top, rear perspective view thereof; FIG. 3 is a bottom, front perspective view thereof; FIG. 4 is a bottom, rear perspective view thereof; FIG. 5 is a front elevation view thereof; FIG. 6 is a rear elevation view thereof; FIG. 7 is a side elevation view of the powered toothbrush handle, the opposite side elevation view being a mirror image thereof; FIG. 8 is a bottom view of the powered toothbrush handle; and, FIG. 9 is a top plan view thereof. The illustrative broken line showing of a brush head accessory throughout the drawing figures depicts an exemplary component which might be used with the powered toothbrush handle and forms no part of the claimed design.
